CLAIM

The ornamental design for a bottle with a cap, as shown and described.

DESCRIPTION

FIG. 1 is a perspective view of a bottle with a cap embodying our new design;

FIG. 2 is a front view of the bottle with a cap shown in FIG. 1;
FIG. 3 is a back view of the bottle with a cap shown in FIG. 1;
FIG. 4 is a left side view of the bottle with a cap shown in FIG. 1;

FIG. 5 is a right side view of the bottle with a cap shown in FIG. 1; and,

FIG. 6 is a top view of the bottle with a cap shown in FIG. 1. The broken lines shown in the drawings illustrate the portions of the bottle with a cap that form no part of the claimed design.

1 Claim, 3 Drawing Sheets
